OIL-TESTING APPARATUS.

1,047,469.

Specification of Letters Patent.

Patented Dec. 17, 1912.

Application filed April 27, 1911. Serial No. 623,601.

To all whom it may concern:

Be it known that I, PAUL WENDT, a citizen of the free town of Lübeck, and resident of 4 Hinter den Hoefen, in the free town of 5 Hamburg, German Empire, have invented new and useful Improvements in Oil-Testing Apparatus, of which the following is a specification.

This invention relates to an improved 10 process and apparatus for testing oils in the presence of steam, gases, hot air or the like and the object is to ascertain whether the oil supply to the gas or fluid is taken up in such a manner thereby that it is finely divided therein or whether a complete separation 15 takes place.

The invention also enables the changes in 20 the character of the oil when mixed with the gases or fluids to be ascertained.

According to the present invention after 25 the oil has been supplied to the gas, fluid or the like, the mixture is caused to traverse over a comparatively long path and any constituents thereof tending to deposit, settle 30 down during the traverse of the mixture. The mixture is supplied to a container within 35 which means are provided for causing the mixture to pass over a comparatively long path in said container before obtaining exit therefrom, the deposits settling within the walls of the container, which is so constructed that it may be readily inspected over its whole length, so that the amount of the deposit and the length of surface over which 40 the same extends can be readily ascertained and, if desired, the deposits may then undergo further tests in a suitable apparatus.

In order that the invention may be more clearly understood reference is made to the 45 accompanying drawings, whereon is shown by way of example the preferred method of carrying out the invention.

Figure 1 is a vertical section through the 50 oil-testing apparatus, Fig. 2 is an elevation 45 partly in section of the inner container and Fig. 3 is a plan view of Fig. 1 with the cover 55 removed.

The apparatus comprises a chamber *w* the 60 walls of which are of suitable thickness and material in order to protect the same from heat radiation and is provided with a cover *v*. Within the chamber *w* is fitted a container *a* preferably of cylindrical form, this container being provided with a cover *d* and having an inlet *f* thereto, this inlet 65

communicating with the inlet *s* of the chamber *w*, being provided with a conical head *m* fitting within the bore-hole of the inlet connection *s*, the connection being maintained by means of a wedge *k* inserted between the wall of the chamber *w* and the container *a*. The chamber *w* is also provided with an outlet connection *z* and a thermometer or the like *y*. The cover *d* of the container *a* is removable but is secured against displacement during testing operations viz.: by means of a spring *x* secured to the cover *v* of the chamber *w*. Within the container *a* are located two inner bodies *b* and *c* both of which are provided with externally projecting ribs *n*, *o* arranged spirally around the same, the breadth of the ribs *n*, *o* being such that the ribs *n* bear against the outer wall of the container *a* and the ribs *o* against the inner surface of the body *b*. 70

The spaces between the ribs *n* and ribs *o* communicate with one another at their upper ends by way of an opening *g* while the lower end of the spiral space formed by the ribs *o* communicates by way of an opening *h* with a central bore hole *i* which is in communication with a central hole *p* in the cover *d* and lateral apertures *e* in a boss *d'* on the cover *d*. The container *a* preferably stands upon a layer of asbestos *t* in the chamber *w*. 75

The method of carrying out the testing is as follows: After the oil has been fed to the steam, gas or other fluid by a suitable dropping arrangement, the mixture flows into the chamber *w* by way of the inlet connection *s* and inlet opening *f* into the spiral chamber between the container *a* and the inner body *b* formed by the ribs *n*, and rising therein, passes through the opening *g* and descends in a spiral path through the space between the inner bodies *b* and *c* formed by the ribs *o*, passing away therefrom through the opening *h* to a central bore hole *i* escaping therefrom into the chamber *w* through the outlets *e* and passing away by way of the outlet connection *z*. According to the nature of the mixture any constituents thereof tending to deposit, settle on the surfaces of the spiral path and the amount and nature of such deposits may then be ascertained by removing the covers *v* and *d* and withdrawing the inner bodies *b* and *c*, while at the same time the length 110

over which such deposits extend may be readily seen and, if desired, such deposits may be removed and subjected to further testing operations in any suitable testing machine.

It will be seen by the foregoing apparatus that a comparatively long path is provided for the mixture within a comparatively small space and that moreover the oil can 10 be subjected to the same conditions therein independently of the nature of the fluid with which it is mixed.

As will be seen from the drawings, the fluid is caused to pass upwardly between 15 the container *a* and inner body *b* and downwardly through the space between the inner bodies *b* and *c* in a spiral manner but, if desired of course, the fluid may be caused to pass over a zig-zag path within the container *a* although the construction hereinbefore described is preferable.

I claim:

1. Apparatus for determining, by separation, the condition of, and changes undergone by oil in the presence of gases or vapors comprising a cylindrical casing having an inlet opening at one end, a loose inner cylindrical hollow body of smaller diameter than said casing having an outlet opening 30 at the end opposite to said inlet opening, a removable cover over said casing having an outlet aperture communicating with the hollow interior of said inner body, and a spiral web between said casing and inner body so 35 as to form an imperforate-walled spiral conduit from said inlet opening to said outlet opening.

2. An apparatus for determining, by separation, the condition of, and changes undergone by, oil in the presence of gases or vapors, comprising in combination an outer container, having an inlet opening at one end, a plurality of removable inner hollow bodies in said outer container fitting the 40 one within the other, said hollow bodies having communicating openings at alternating ends, a removable cover over said container having an outlet aperture communicating with the hollow interior of the innermost body, and spiral webs between said inner bodies so as to form an 45 most body, and spiral webs between said container and the outermost inner body and between said inner bodies so as to form an

alternating spiral conduit from said inlet opening to the interior of said innermost body.

3. An apparatus for determining, by separation, the condition of, and changes undergone by, oil in the presence of gases or vapors, comprising, in combination, an outer cylindrical container having an inlet opening at one end, a plurality of removable cylindrical inner hollow bodies in said outer container fitting the one within the other, said hollow bodies having communicating openings at alternating ends, a removable cover over said container having an outlet aperture communicating with the hollow interior of the innermost body, a spiral web on the outermost inner body extending to said container, and spiral webs projecting 60 from each of the other inner bodies and extending across the spaces between said inner bodies so as to form an alternating spiral conduit from said inlet opening to the interior of said innermost body.

4. An apparatus for determining, by separation, the condition of, and changes undergone by, oil in the presence of gases and vapors, comprising, in combination, an outer cylindrical container having an inlet opening at one end, a plurality of removable cylindrical inner bodies in said outer container fitting one within the other, said hollow bodies having communicating openings at 70 alternating ends, a removable cover over said container having an outlet aperture communicating with the hollow interior of the innermost body, a spiral web on the outermost inner body extending to said container, spiral webs projecting from each of the other inner bodies and extending across the spaces between said inner bodies so as to form an alternating spiral conduit from said inlet opening to the interior of said innermost body, an exterior casing surrounding said outer container and having inlet and outlet connections and a removable lid on said exterior casing.

In witness whereof I have hereunto set my hand in the presence of two witnesses: PAUL WENDT.

Witnesses:

CESAR SOMMER,
ADOLF GRAUMANN.
